SELF-HEATING CONTAINER HAVING
HERMETIC SEALING MEANS

Eugene J. Rivoche, Washington, D. C.

Application November 3, 1950, Serial No. 193,866

8 Claims. (Cl. 126—263)

1

This invention relates to self-heating containers for packaged food or other material of the type which contains, in a compartment separate from but adjacent the packaged-material compartment, burnt lime or other exothermic material which on reaction with water will liberate sufficient heat to raise the temperature of the packaged material to a predetermined extent. Such containers are well adapted for use under conditions where the usual means for preparing hot foods are not available.

In manufacturing such containers, the amount of burnt lime, mixtures containing the same, or other exothermic material, which is used is just sufficient when activated with water to raise the temperature of the food or the like to a predetermined degree. Consequently, the exothermic material should be hermetically sealed to prevent absorption of moisture from the atmosphere and such resultant deterioration of the exothermic material as would prevent it from liberating the desired amount of heat. To that end, the invention contemplates a self-heating container of simple construction and ease of manufacture and assembly in which the compartment for the exothermic material is effectively and hermetically sealed.

If the self-heating container is one which carries an adequate amount of water to activate the exothermic material, the sealing means will effectively seal the compartment for the exothermic material both from such water and from the atmosphere; while if the self-heating container is one to which water from an extraneous source must be added, it is only necessary that the sealing means hermetically seal such compartment from the atmosphere.

The use of burnt lime as the exothermic material is preferred as it is cheap, liberates a large amount of heat, is readily available, and is easy to handle in manufacturing self-heating containers. However, burnt lime, on reaction with water, expands to several times its normal volume. Hence, when burnt lime is utilized as the heating material it is necessary that some means be provided to permit at least partial expansion of the lime, or else the container must be constructed of material stronger than that normally used in tins for the canning of food. Leaving sufficient free space in the lime compartment to permit sufficient expansion of the lime so that the use of stronger stock for the container is not necessary is undesirable as it adds to the overall size of the self-heating container, a disadvantage from the standpoint of transportation.

2

In accordance with the present invention, the food container is mounted for telescopic movement in an outer container and the hermetic sealing means is formed between cooperating portions of the food container and the outer container, and is effective to maintain the desired hermetic seal until the self-heating container is to be put into operation, if the container carries the activating water, or if it doesn't carry the water, until the expansion of the lime builds up a predetermined pressure, when it automatically is broken to permit telescopic movement of the food container.

The invention will be further described in connection with the accompanying drawing, but it is to be understood that such further description is by way of exemplification, and the invention is not limited thereby, other than to the extent set forth in the appended claims.

20 In the drawings:

Fig. 1 is a vertical sectional view of a self-heating container embodying the invention and containing water to activate the exothermic material, and

25 Fig. 2 is a view similar to Fig. 1 of a self-heating container embodying the invention, but of that type in which water from an extraneous source is used to activate the exothermic material.

30 In the drawings, the container 1 for food, soup, or any other material which it may be desired to heat without the use of heat from extraneous source, which material hereinafter will be referred to as "food," preferably is formed of the usual tinned or lacquered metal stock commonly used in the canning industry.

35 The food container 1 is nested in an outer container 2 for limited telescopic movement, as hereinafter described. The outer container consists of a bottom 3 and a side wall 4, but no top. The side wall 4 terminates short of the upper end of the food container a distance sufficient to enable one to get a good grip on the protruding end of the food container. The upper edge 40 portion of the side wall 4 lies against and is sealed to the side wall of the food container. Such sealing preferably is obtained by a sealing strip of rubber, plastic, or other adhesive material 5 which readily may be removed when the container is to be put into operation.

45 The side wall 4 is circumferentially grooved or otherwise distorted to provide inwardly-protruding, vertically-spaced extensions 6, 7 and 8. The extension 6 has a substantially flat horizontal upper surface 9 which forms a seat for a

sealing ring or gasket 11 of rubber or other resilient sealing material, against which the lower portion of a cooperating sealing flange 12 of the food container is maintained in hermetic sealing engagement.

The grooving to form the extension 7 is less abrupt and less deep to form a gradually inwardly-tapering portion 13 which partially overlies the sealing flange 12 and normally holds the flange 12 in tight sealing engagement with the sealing ring 11.

The upper extension 8 also is less deep than the extension 7 and has a substantially horizontal under surface 14, which on telescopic movement of the food container 1 outwardly of the outer container 2 is engaged by the flange 12 and limits outward movement of the food container.

The space between the bottom of the food container and the bottom of the outer container forms a compartment of such size as to receive 20 an amount of lime or other exothermic material 16 just sufficient, when activated, to heat the food in the food container to the desired temperature.

In this form of the invention, water 17 for activating the lime is stored in the space between the side walls of the food container and the outer container.

When it is desired to place the self-heating container in operation, it is only necessary to remove the sealing strip 5 and to grip the upper end of the food container and pull it upwardly until the flange 12 is pulled past the extension 7; the gradual taper of the portion 13 and the inherent resiliency of the thin metal stock from which the side wall of the outer container is formed make this operation relatively easy.

Once the flange 12 has been pulled above the extension 7, the water will flow into the lime compartment and activate it with the liberation 40 of heat sufficient to raise the temperature of the food in the container 1 to a desired eating temperature.

The expanding lime will lift the food container until the flange 12 strikes the limiting surface 45 14 when outward movement of the food container in the outer container will be arrested, as indicated in dotted lines in Fig. 1. The pressure exerted by the lime will cause a pressure contact between the flange 12 and the surface 14 which will prevent any of the lime being forced past the extension 8.

The gradual downward taper of the upper surfaces 18 and 19 of the extensions 8 and 7, respectively, enable the food container to be forced inwardly past the extensions 8 and 7 during assembly, to cause the flange 12 to be brought into tight sealing contact with the sealing ring 11.

The form of the invention illustrated in Fig. 2 is the same as that illustrated in Fig. 1, except that the water is not stored in the space between the side walls of the food container and the outer container and must be added from an extraneous source.

To facilitate the use of an amount of water 65 sufficient to give maximum liberation of heat by the exothermic material, the bottom 3' of the outer container 2' is dished to provide a space, when the container is inverted, of just the right size to hold an amount of water to most effectively activate the exothermic material.

The dished bottom 3' is formed with slight indentations 21 into which the pointed end of a puncturing tool may be placed to facilitate the puncturing of the bottom wall to form holes 75

therethrough through which water may pass to be absorbed by and react with the exothermic material.

In all other respects the self-heating container of this form of the invention is the same as that of Fig. 1, and like parts are designated with the same reference characters, primed.

When the self-heating container of this form of the invention is to be put into operation, it is inverted, the dished bottom 3' punctured with a suitable tool and filled with water. As soon as the water has passed through the holes and is absorbed by the lime the container is turned right side up again and left until the heat liberated by the lime has heated the food to a sufficient temperature for eating.

In either form of the invention, the food container may be opened before it has been heated to a temperature such as will make its handling difficult, or it may be left sealed until the food is heated to the eating temperature. If opened at the beginning of the heating operation, access can be had to the food for stirring during the heating thereof.

I claim:

1. A self-heating container comprising an inner container for food, an outer container having a bottom and a side wall in which said food container is mounted, the side wall of the outer container having an inwardly-extending peripheral extension, the inner container being supported by said extension, a water-tight seal between the inner container and said extension, and material which on reaction with water liberates heat between the bottom of the food container and the bottom of the outer container.

2. A self-heating container as defined in claim 1 in which the extension has a generally horizontal upper surface, and the water-tight seal comprises a gasket between said surface and the bottom of the food container.

3. A self-heating container as defined in claim 1 in which the water-tight seal is a sealing gasket and in which means are provided for forcibly holding the food container against the sealing gasket.

4. A self-heating container as defined in claim 1 in which the water-tight seal is a sealing gasket and in which releasable and resilient means are provided for forcibly holding the food container against the sealing gasket.

5. A self-heating container as defined in claim 4 in which a portion of the side wall of the outer container overlies a portion of the food container to releasably and forcibly hold the food container against the sealing gasket.

6. A self-heating container as defined in claim 5 in which both the food container and the side wall of the outer container have cooperating inwardly and upwardly extending portions just above the extension which cause the food container to be releasably and forcibly held against the sealing gasket.

7. A self-heating container as defined in claim 1 in which the food container is mounted for telescopic movement in the outer container and the upper portion of the side wall of the outer container has an inward extension for engagement by an outward extension of the food container to limit outward telescopic movement of the food container in the outer container.

8. A self-heating container as defined in claim 1 in which water to activate the heat-liberating material is sealed in the space between the side walls of the food container and the outer con-

5

tainer, at the side of said water-tight seal remote from the heat-liberating material.
